ATTORNEY

UNITED STATES PATENT OFFICE.

CHARLES W. UNGER, OF LOS ANGELES, CALIFORNIA.

DESIGN FOR A MEMORIAL-SERVICE POSTER OR SIMILAR ARTICLE.

52,999.

Specification for Design.

Patented Feb. 11, 1919.

Application filed October 24, 1918. Serial No. 259,593. Term of patent 3½ years.

To all whom it may concern:

Be it known that I, CHARLES W. UNGER, a citizen of the United States, residing at Los Angeles, in the county of Los Angeles and State of California, have invented a new, original, and ornamental Design for Memorial-Service Posters or Similar Articles, of which the following is a specification, reference being had to the accompanying drawing, forming part thereof.

The figure is a face view of a memorial service poster or similar article, showing my design.

I claim:

The ornamental design for a memorial service poster or similar article, as shown.

CHARLES W. UNGER.

Witnesses:

EDMUND A. STRAUSE,
MARY A. SPELTA.
